UNITED STATES PATENT OFFICE.

LOUIS H. BRINKMAN, OF GLEN RIDGE, NEW JERSEY, ASSIGNOR TO BALL ROLLED
TUBE CORPORATION, A CORPORATION OF NEW YORK.

METAL-DRAWING APPARATUS.

1,360,087.

Specification of Letters Patent. Patented Nov. 23, 1920.

Application filed August 29, 1917. Serial No. 188,709.

To all whom it may concern:

Be it known that I, LOUIS H. BRINKMAN, a citizen of the United States, residing at Glen Ridge, county of Essex, and State of New Jersey, have invented new and useful Improvements in Metal-Drawing Apparatus, of which the following is a specification.

This invention relates to the reduction of metal tubes or rods by drawing them through a die having balls operating upon the metal, and is an improvement upon the disclosures of my Patents Nos. 1,143,101 and 1,203,306, dated June 15th, 1915 and October 31st, 1916, respectively.

Where, as in the patents above referred to, the die and work are relatively rotatable, the rotation of the work on the one hand and the die parts on the other being the same for all of the die parts which bear upon the balls, the area of contact of a ball with the work and with the coöperating parts of the die, is apt to be confined to a comparatively narrow zone on the ball. The wear being thus restricted instead of distributed over the area of the ball, continued use of the apparatus may in time produce irregularly shaped balls which are not best adapted for the operation of the device.

It is one object of the invention to provide apparatus for distributing the wear over the surfaces of the balls.

It is further found that in prior structures of the character above referred to, the balls have no tendency to roll lengthwise of the tube. This requires that the work be drawn under the balls by main strength of the draw head which places great stress on the apparatus and work. The latter is usually heated and if it is sufficiently softened by the heat and the pull is sufficient the tube or rod may be stretched or even parted. The present invention provides methods and means for altering the rotation of the balls so that a component of the rolling motion of a ball is lengthwise of the work so that it tends to climb upon the metal shoulder on the work against which it bears. This reduces the opposition to the drawing of the work through the die and it is possible that under some circumstances the metal would be drawn into the die by the operation of the balls on it without the necessity for a draw head. The invention may also be employed to effect various other controlling influences

on the movement of the balls according to the results desired to be accomplished.

Other and ancillary objects of the invention will appear hereinafter.

In the accompanying drawings, which 60 illustrate the invention,

Figure 1 is a side elevation of apparatus embodying the invention.

Fig. 2 is a top plan view of the apparatus of Fig. 1;

Fig. 3 is a longitudinal central section, on an enlarged scale, of the die and appurtenant parts; and

Fig. 4 is a section on the line 4—4 of Fig. 3.

Referring to the drawings, and first to Figs. 1 and 2, 1 is a platform or table at one end of which is mounted a rotary electric motor 2 for driving a die mechanism 3 on a support 4. To the left of this mechanism 75 is provided a furnace 5, such as a gas furnace. This furnace is hollow so as to permit the insertion therethrough of a mandrel 6 when tubes are being drawn and to receive a tube 7 to be heated and drawn. 80

Upon the table 1, is a trackway 8, which extends along the table in alignment with the die. A draw-head 9 and a following block 10 are mounted on the trackway, and the following block is provided with a pair of tongs 12 having gripping jaws 13 adapted to grip on to a plug or other suitable means 14 secured in the end of the tube 7 to be drawn, while the other extremity of the tongs is provided with toggle links and a connecting hook 15, connecting the tongs to the draw-head 9 which is in turn provided with a pivotal hook 16, having a handle 17, by means of which it is lifted into and out of 95 connection with an endless chain 18, passing over sprocket wheels 19 and 20 mounted near the two ends of the table. The chain is driven by means of a suitable electric motor 21, geared to the sprocket wheel 20, 100 through the gear wheels 22, 23, 24 and 25.

When the machine is used for drawing tubes instead of rods, I provide the mandrel 6, above referred to, and this is supported at one end in an open slot 26 in the head 105 of a pillow block 27. The mandrel is preferably of considerably less diameter than the tube to be drawn and extends through the furnace 5 to the ball die mechanism proper, and is provided with an enlarged 110

head 28, lying within the ball die mechanism and of the desired inner diameter of the finished tube.

Referring now particularly to Figs. 3 and 4, a succession of die balls 29 surround the tube 7 to be operated upon. Surrounding the balls is a race-ring 30 having an inclined interior surface so that by shifting it longitudinally, the balls may be forced 10 inwardly or permitted to move outwardly to vary the diameter of the die. The race-ring 30 is splined in a recess in the member 31, this recess being closed at the end by means of a ring 32 secured to one end of the member 31. The other end of the member 31 is provided with a collar or nut 33, bearing against the support 4 and so preventing movement of the member 31 and its carried parts, to the left (see Fig. 3) while the 20 longitudinal movement of this member in the other direction is limited by its shoulder 34 coming against the frame 4. Shims 35 may be interposed between the shoulder 34 and the frame 4 for purposes of adjustment. 25 The ring 30 is secured between the head 32 and the shoulder 36 on the member 31 and this may be effected by the inter-position of shims 37, longitudinal adjustment of the ring being capable of accomplishment by 30 withdrawing one or more shims from one side of the ring and inserting them on the other side.

The member 31 is driven by means of a herringbone gear 38 fixed to it and meshing 35 with a gear 39 fixed on the shaft 40 which is an extension of the shaft of the motor 2. It will be observed that the member 31 is rotatably mounted in a bushing 41 in the frame 4.

40 The head 32' is screw threaded in the frame so that it is adjustable and is locked thereto by the jam nut 43. This head extends within the ring 32 and the face 56 at its inner end serves to hold the balls in position. While this face serves to prevent 45 displacement of the balls, it does not sustain any considerable pressure during the drawing operation as the tendency of the work is to force the balls in the opposite 50 direction.

Rotatably mounted within the member 31 is a sleeve 44 having fixed to it at one end the gear 45, also preferably of the herringbone type, which engages with the gear 46 55 on the shaft 40. A ball bearing 47 is interposed between the hub of the gear 45 and the frame to take up the thrust. At its other end the sleeve 44 has fixed to it the cheek plate 48, against which the balls bear. This 60 cheek plate is provided with radial ribs 49 forming cavities for the balls so that as the plate is turned the balls will be carried with it circumferentially of the die. This permits the balls to be adjusted radially to 65 vary the diameter of the die. At its interior

edge the plate has a lip or flange 50 to prevent the balls from falling out of the die when the work is withdrawn.

To aid in keeping the balls cool a circumferential groove 51 in the head 32', and 70 which is closed on one side by the part 42 of the frame, is supplied with a cooling fluid, such as water, from any suitable source, by means of a pipe 52. This circumferential groove 51 communicates by 75 passages 53 of which there may be any suitable number distributed circumferentially about the head, with a circumferential chamber 54 from which the fluid flows through passages as 55, to the face 56 against which the balls 80 bear. The fluid thus introduced to the balls, is thrown outwardly by centrifugal action and passes out from the ball cavity through the annular passage 57 formed by the clearance between the head 32' and the rotating 85 part within which it enters which discharges into the circular chamber from which it may be drained off by means of a pipe 59.

The gears 38 and 39 are made of such 90 ratio and the speed of the motor is such that the race-ring 30 is driven at the desired rate of speed which would ordinarily be a high speed to effect the desired results. The tube having passed through the furnace, is heated to the desired degree and is drawn 95 through the die within the encircling balls by the drawhead as before referred to—it being of course understood that the ring 30 has been so adjusted longitudinally of the apparatus, by means as before referred to, 100 that the diameter of the die is such as to effect the desired reduction.

The gearing is such that the plate 48 rotates at a number of revolutions per minute which is slightly larger than one-half of the 105 number of revolutions per minute of the ring 30. As the ring 30 rotates, the balls tend to be rolled thereby in a path circumferentially of the work, that is, about axes more or less parallel to the axis of the work, 110 and the center of a ball moves in its circumferential path at a speed substantially one-half that of the ring 30. As the surface of the plate 48 is substantially radial at the points where it engages the balls, this plate 115 would have no turning effect on the balls if run at a number of revolutions per minute, one-half those of the ring 30. Under such circumstances, the plate 48 would simply rotate along side the balls at the same 120 speed at which they were driven about the work by the ring 30. By varying the speed of the plate 48 so that its revolutions are either above or below those of the ring 30, a turning force is exerted upon the balls 125 which tends to rotate them about axes more or less radial to the work and imparts to them a resulting rolling movement having a component extending longitudinally of the tube. This causes the wear to be distributed 130

over the surfaces of the balls so that the wear is not all confined to a restricted zone. Where the plate 48 is rotated in the same direction as the ring 30, the longitudinal 5 component, before referred to, is in such direction that the balls continually tend to climb upon the shoulder of the work against which they bear and aid the drawing of the work through the die as has been before referred to. It will be seen that the relative 10 speeds of the plate 48 and the ring 30 may be made to vary within wide limits, that they may rotate in the same or opposite directions, or that one only of them might be referred to. It will be seen that the relative speeds of the plate 48 and the ring 30 may be made to vary within wide limits, that they may rotate in the same or opposite directions, or that one only of them might be 15 referred to. It will be seen that the relative speeds of the plate 48 and the ring 30 may be made to vary within wide limits, that they may rotate in the same or opposite directions, or that one only of them might be referred to. It will be seen that the relative speeds of the plate 48 and the ring 30 may be made to vary within wide limits, that they may rotate in the same or opposite directions, or that one only of them might be 20 referred to. It will be seen that the relative speeds of the plate 48 and the ring 30 may be made to vary within wide limits, that they may rotate in the same or opposite directions, or that one only of them might be referred to. It will be seen that the relative speeds of the plate 48 and the ring 30 may be made to vary within wide limits, that they may rotate in the same or opposite directions, or that one only of them might be 25 referred to. When hot tubes are to be drawn with the apparatus, the mandrel 6 is made in the form of a hollow tube having the enlarged head 28 hollow, and through the hollow mandrel is passed a small tube 60, preferably extending from the tail-end of the mandrel and through the same to the enlarged head. This tube is connected with a suitable source of cooling fluid 61 from which water will be discharged into the tube whence it 30 will flow to the hollow head and out again through the hollow mandrel. This flow of water will prevent the mandrel from becoming over heated by the furnace and the hot tube. 35 While the invention has been illustrated in what is considered its best application, it is to be understood that the apparatus may have other embodiments without departing from the scope of the claims; the invention is not therefore limited to the structure 40 shown in the drawings, the invention being pointed out in the appended claims as required by the patent statutes.

What I claim is—

- 50 1. A ball die mechanism for drawing metal, having in combination a series of balls for acting upon the work, means for rolling the balls circumferentially about the work and means for giving the rolling of the balls a component lengthwise of the work.
- 55 2. A ball die mechanism for drawing metal, having in combination a series of balls for acting upon the work, means for rolling the balls circumferentially about the work, means for giving the rolling of the balls a component lengthwise of the work, and opposite to the direction in which the tube is drawn.
- 60 3. A ball die mechanism for drawing metal, having in combination a series of

balls for acting upon the work, means for rolling the balls circumferentially about the work, means for giving the rolling of the balls a component lengthwise of the work, and means for adjusting the balls to vary 70 the diameter of the die.

4. A ball die mechanism for drawing metal, having in combination a series of balls for acting upon the work, means for rolling the balls circumferentially about the 75 work, means for giving the rolling of the balls a component lengthwise of the work, and means for applying cooling fluid to the balls.

5. A ball die mechanism for drawing 80 metal, having in combination a series of balls for acting upon the work, a support for the balls comprising a plurality of separately movable parts against which the balls bear and means for rotating said parts and 85 the work at different speeds.

6. A ball die mechanism for drawing metal, having in combination a series of balls for acting upon the work, means for rolling the ball circumferentially about the 90 work, means for giving the rolling of the balls a component lengthwise of the work, and a common driving means for the aforesaid means.

7. A ball die mechanism for drawing 95 metal, having in combination a series of balls for acting upon the work, means for rolling the balls circumferentially about the work and means for increasing the area of wear on the balls over that occasioned by 100 circumferential rolling.

8. A ball die mechanism for drawing metal, having in combination a series of balls for acting upon the work, a support therefor, and means for increasing the area 105 of wear on the balls over that occasioned by circumferential rolling.

9. A ball die mechanism for drawing metal, having in combination a series of balls for acting upon the work, a support 110 for the balls comprising a plurality of separately movable parts against which the balls bear and means for causing rotation of said parts at different speeds with relation to the work, the moving parts rotating in the 115 same direction.

10. A ball die mechanism for drawing metal, having in combination a series of balls for acting upon the work, a support for the balls comprising a plurality of separately movable parts against which the balls bear, means for causing rotation of said parts at different speeds with relation to the work, and means for preventing relative movement circumferentially of the work 120 of the balls and one of the rotating members.

11. A ball die mechanism for drawing metal, having in combination a series of balls for acting upon the work, a support for the balls comprising a plurality of 125

separately movable parts against which the balls bear, means for causing rotation of said parts at different speeds with relation to the work, and means for preventing the said balls from moving circumferentially of the work with relation to one of the said rotating parts of lesser speed.

12. In a ball die mechanism for drawing metal, the combination with a series of balls 10 adapted to bear upon the work; of a race-ring bearing upon the balls; means for rotating said race-ring; another rotative member bearing upon said balls and means for rotating said member at a speed different 15 from that of said race-ring.

13. In a ball die mechanism for drawing metal, the combination with a series of balls 20 adapted to bear upon the work; of a race-ring bearing upon the balls; means for rotating said race-ring; another rotative member bearing upon said balls and means for rotating said member at a speed different 25 from that of said race-ring, said member carrying means for preventing movement, circumferentially of the work, of the balls with relation to said member.

14. A ball die mechanism for drawing metal, having in combination a series of balls for acting upon the work, a race-ring 30 engaging the balls substantially opposite the points at which they engage the work, means for rotating said race-ring, a member bearing upon said balls substantially midway between their points of engage-

ment with said race-ring and the work, said member having ribs to prevent relative movement of said member and said balls circumferentially of the work and means for rotating said member in the same direction as said ring and at a rotative speed greater 40 than one-half that of said ring.

15. A ball die mechanism for drawing metal, having in combination a series of balls for acting upon the work, ball-actuating means tending to rotate the balls on axes 45 more or less parallel to the axis of the work, and ball-actuating means tending to rotate the balls on axes more or less radial to the work, whereby the balls are caused to rotate on axes resulting from the said ball 50 actuating means.

16. In a ball die mechanism for drawing metal, in combination, a series of balls to encircle the work, ball-actuating means for causing the balls to roll around the work 55 whereby the balls tend to rotate on axes more or less parallel to the work, ball-actuating means tending to rotate the balls on axes more or less radial to the work, and means for passing the work longitudinally 60 through the die, whereby the balls are caused to rotate on axes which are the resultants of the forces exerted on the balls by the aforesaid means.

In testimony whereof I have signed this 65 specification this 25th day of August, 1917

LOUIS H. BRINKMAN.
